(57) **CLAIM**

The ornamental design for a drain screed device as shown and described.

DESCRIPTION

FIG. 1 is a perspective view of the drain screed device; FIG. 2 is a front side view of the drain screed device of FIG. 1;

FIG. 3 is a rear side view of the drain screed device of FIG. 1;

FIG. 4 is an end view of the drain screed device of FIG. 1; FIG. 5 is another end view of the drain screed device of FIG. 1;

FIG. 6 is a top view of the drain screed device of FIG. 1; FIG. 7 is a bottom view of the drain screed device of FIG. 1;

FIG. 8 is a perspective view of another drain screed device; FIG. 9 is a front side view of the drain screed device of FIG. 8;

FIG. 10 is a rear side view of the drain screed device of FIG. 8;

FIG. 11 is an end view of the drain screed device of FIG. 8; FIG. 12 is another end view of the drain screed device of FIG. 8;

FIG. 13 is a top view of the drain screed device of FIG. 8; and,

FIG. 14 is a bottom view of the drain screed device of FIG. 8.

The dash-dot-dash broken lines represent symbolic break lines and the dash-dash-dash broken lines represent portions of the drain screed device. The symbolic break lines and any portions of the drain screed device between the symbolic break lines in FIGS. 1-3, 6-10, 13 and 14 and the broken lines in FIGS. 1-6 and 8-10 form no part of the claimed design.
